UNITED STATES PATENT OFFICE.

LORENZO G. HOWARD, OF PROVIDENCE, RHODE ISLAND.

SPARK PLUG.

1,415,447.

Specification of Letters Patent.

Patented May 9, 1922.

Application filed June 15, 1920. Serial No. 389,194.

To all whom it may concern:

Be it known that I, LORENZO G. HOWARD, a citizen of the United States, residing at Providence, in the county of Providence and 5 State of Rhode Island, have invented certain new and useful Improvements in a Spark Plug, of which the following is a specification.

My invention relates to a spark plug.

10 Among the important objects may be mentioned, the provision of an article of this type which can hardly fail to fire either in oil or grease; will produce five or any plural- ity of sparks practically simultaneously; one 15 having electrodes preferably shaped so as to retain the porcelain should the same break so that it cannot become dislocated or fall into a position where it can score the cylinder of the engine; one having a visible gap 20 means whereby the condition or action of the plug may be readily observed; one in which said means will be in the nature of an intensifier and have its parts covered and protected from the entrance of material which 25 might short-circuit it and one of the generally improved, simplified and more efficient construction hereinafter described and illustrated in accompanying drawings of one preferred embodiment, wherein:

30 Figure 1 is an elevation of the improved plug;

Figure 2 is an enlarged vertical sectional view of the plug;

Figure 3 is a plan view of the insulating 35 core; and

Figure 4 is an enlarged bottom view of the plug.

Referring specifically to the drawings, 5 designates the core or plug body, which is 40 of insulating material of any preferred kind, for instance, porcelain. Removably and centrally located in the core is an electrode 6 having a head 7, preferably substantially conical as shown and being relatively wide 45 to overlap the bottom of the core so as to be incapable of movement upwardly thereinto. Electrode 6 may be removed by downward movement. Resting upon the core is a cage or insulating body 8, for instance of porcelain, provided with a transverse slot or window 9. The cage is also provided with a depression or recess which receives a projection 10 of the core to assist in centering and positioning the core and cage relatively. A 50 central opening is also provided in the cage to removably receive the electrode 6. Dis-

posed in the window 9 is a nut 11 which engages screw threads on electrode 6 to secure that electrode in place and secure the core and cage together removably. 60

Also removably mounted in the cage 8 in alignment with electrode 6 and in relatively close relation therewith as shown is an electrode section 12, fastened in place by a nut 13 disposed in the window and engaging 65 screw threads on the section 12 and by a nut 14 engaging screw threads on section 12 and resting on top of the cage. A binding nut 15 cooperates with the nut 14 to connect a wire or conductor to the electrode 70 sections 12—6, and it rides on the same screw threads as nut 14.

It will be noticed that a spark gap is provided between the electrode sections 6 and 12 which will serve to intensify the spark. 75 Also this particular means being located in the window of the cage may be observed at all times to ascertain the working efficiency thereof. It is preferably protected by means which will prevent the entrance of 80 short-circuiting material and it may be in the nature of a mica or other transparent tube 16 into which projections 17 and 18 on the nuts 11 and 13 respectively extend to removably mount it. 85

Embedded in the core 5, are a plurality of electrodes 19, preferably hooked at 20 to facilitate anchorage in the core. The core has openings or recesses shaped like the hook ends 20 and thus the electrodes 19 need not 90 be fastened permanently in the core. They cannot become displaced since cage 8 rests on them. At the lower extremities these electrodes 19 are preferably offset and curved as at 21 to provide spark gaps between them and so that one of them at 22 will be in spark gap relation with electrode 6 at the head 7. Also one of the portions 21 is in spark gap relation with an electrode 23 carried in any suitable manner by a bushing or shell 24 to be grounded as usual to the motor casing. 95 100 105

Said bushing or shell 24 may be of any desired shape but is preferably provided with screw threads at 25 whereby it may be 105 screwed into the motor casing and with a suitable wrench-engaging portion 26.

Core 5 preferably has an outwardly extending annular rib or ring 27 integral with it which extends into an enlarged 110 chamber 28 provided within the shell 24 and rests on a ledge 29 therein. A gland

30, provided with a wrench-engaging head 31 may extend into the chamber to engage the ring 27 to secure the core to the shell. The shell and gland are preferably screw 5 threaded to each other at 32. Gaskets 33 may be provided on opposite sides of the ring 27 in order to provide a gas-tight joint at this point.

In use, the gap between the electrode 10 sections 6 and 12 may be observed when desired to ascertain whether or not the cylinder to which the plug applies is firing. The circuit is formed from the battery or magneto or other source through a conductor 15 connected by the nut 15 to electrode 12 jumping therefrom and becoming intensified at the gap between it and electrode 6, to the electrode 6 to the portions 21 and 22 to electrode 23 to the shell which is grounded 20 as described. A plurality of sparks will be given, one at each of the gaps between the portions 21, 22 and 23 as will be understood.

It will be noticed that the electrodes 19 at the portions in the core 5 are straight. 25 This construction permits equal or even contraction and expansion of the core so as to minimize the chances of cracking. Should it crack, however, these electrodes 19 will serve to retain the fragments together so that 30 they cannot fall into the cylinder or reach the same in any way to injuriously score it.

Since merely the preferred embodiment of the invention has been illustrated and

described, it is to be understood that changes in the details of construction, combinations and arrangements of the parts may be resorted to within the spirit and scope of the invention as defined by appended claim.

I claim:

A spark plug having a core, an electrode 40 loosely mounted therein, a cage resting on the core and said electrode, interengaging means intermediate the core and cage, a second electrode, said second electrode being 45 loosely mounted in the core and said cage, a head on the second electrode to underlap the core and to cooperate with the first electrode, the cage having a window, a nut in said window engaging the second electrode to prevent displacement thereof, a 50 third electrode, said third electrode being mounted by the cage and having a fastening nut in said window, projections on the nuts in said window, a visual protector for 55 the electrodes in said window and into which said projections extend to mount it, a bushing, means to secure the core to the bushing, and electrode means on the bushing to cooperate with the said electrodes. 60

In testimony whereof, I have affixed my signature in the presence of two witnesses.

LORENZO G. HOWARD.
